PROPELLER SHAFT LUBRICATING APPARATUS

Harold A. Guthans, Mobile, Ala.

Application July 21, 1933, Serial No. 681,582

2 Claims. (Cl. 308—36.2)

This invention relates to improvements in lubricating apparatus for the propeller shaft of watercraft and stern bearings thereof.

As will be more fully apparent from the following detailed description, the invention contemplates the provision of means for forcing grease or other lubricant to the outboard bearing under pressure against the force exerted on packing by a spring-pressed gland, the arrangement being such that sand, grit and water are kept out of the bearing and at the same time wear on the packing is automatically compensated for.

One embodiment of the invention is illustrated in the accompanying drawings, in which—

Fig. 1 is a longitudinal section through the stern portion of a twin screw ship, parts being broken and omitted in the interest of clearness; Fig. 2 is a fragmentary detail section on line 2—2 of Fig. 1 illustrating means for driving a pump from the propeller shaft, which pump in turn actuates the piston of a lubricating device; Fig. 3 is an enlarged detail in longitudinal section through the shaft bearing illustrating the improved spring-pressed gland and related parts; Fig. 4 is a transverse section on line 4—4 of Fig. 3; Fig. 5 is a longitudinal section on line 5—5 of Fig. 4; Fig. 6 is a transverse section on line 6—6 of Fig. 3; Fig. 7 is a detail view of the gland and its casing, the upper half of each being shown in side elevation and the lower half in central longitudinal section, the view also illustrating the relative positions of a certain guide pin and its spring and a special fastening bolt to be hereinafter described; Fig. 8 is a detail end view of the gland as viewed from the left of Fig. 7.

Referring in detail to the drawings, 8 represents a propeller of a ship, carried by shaft 10 which carries shrunk-on sleeves 12 and 14 of high carbon steel. These sleeve portions revolve, respectively, in the outboard bearing 16 and the inboard bearing 17. The outboard bearing is carried by a hub 18 formed in part of conventional type of strut casting 20 suitably secured to the ship's framing. The usual stern tube 22 surrounds that portion of the shaft located between the bearings 16 and 17 and suitable hull plating 24 is secured in a conventional manner to the stern frame 26.

The present invention is concerned chiefly with the lubricating apparatus for the outboard bearing and further description of the ship structure is, therefore, unnecessary for a full understanding of the invention.

Located within the hull of the ship, the shaft 10 carries an eccentric 28 which is connected through eccentric strap 30 and pitman rod 32 with an arm 34 carrying a pawl 36 which contacts with a ratchet wheel 38 constituting a drive for a pump 40. This pump is of known construction and need not be described in detail, except to say that it is driven from the shaft 10 and draws liquid from a supply tank 42 by way of pipe 44 and forces such liquid through pipe 46 into the chamber 48 of the lubrication cylinder 50 so as to force the piston 52 therein upwardly. The chamber 54 on the opposite side of the piston contains a quantity of lubricant such as grease or the like supplied in a manner hereafter described. When the pump moves the piston 52 up, such lubricant is forced through a duct 56 to the interior of the bearing 16, thus lubricating the shaft and its bearing. This lubricant, being forced under a constant pressure so long as the shaft is rotating, serves to prevent sand and grit from entering the bearing.

The bearing is provided with a recessed portion 58 to accommodate several turns of plaited raw hide packing 60 as well as the end of a slideable gland 62. This gland is yieldingly pressed into engagement with the packing by a number of springs 64 so that as the packing rings gradually wear away, the gland follows up the wear and insures proper fit between the packing and the shaft throughout the life of the packing. The spring pressure also counteracts to some extent the pressure exerted by the lubricant.

The gland is formed with a plurality of outwardly extending lugs 66 which slidably engage grooves 68 formed in the gland casing 70 which encloses the gland. The casing 70 is secured to the bearing by bolts 72 (see Fig. 5) having intermediate head portions 74 which engage a flange 76 formed on the bearing and thus serve to bolt the bearing to the hub 18. The heads 74 of these bolts are accommodated in recesses 78 formed in the gland casing. The outer shanks 80 of the bolts 72 pass through openings in lugs 82 on the gland casing and nuts 84 serve to rigidly secure the casing to the bearing as will be clear from the drawings.

The springs 64 which yieldingly press the gland against the packing are guided on pins 86 having shoulders abutting the end wall 88 of the gland casing, these pins being riveted over as indicated at 90 so as to securely fasten them to the casing, as indicated clearly in Fig. 3. The free ends of the pins slidably engage longitudinal holes 90 55

formed in the gland, these holes being centered in two instances with the lugs 66, as shown at 92 in Figs. 7 and 8.

Where the spring guide pins align the lugs, 5 the latter are arranged as indicated at 94 in Fig. 7 to accommodate the springs 64. As thus constructed, it is clear that the spring-pressed longitudinally movable gland is entirely enclosed by the casing and that because of the provision 10 of the guide lugs, which slidingly engage the recessed parts of the casing, the spring pins and springs are relieved of strains which might be set up due to the tendency of the shaft to rotate the gland, although normally such tendency of the 15 gland rotation is overcome by the presence of a lubricant which is being constantly extruded in small quantities between the gland and the shaft.

In some cases, I provide a shell-like guard plate 20 comprised of two semi-circular plates which encircle the gland casing, said plates being indicated at 91 in Fig. 3. This plate is electrically welded to the rear end of the bearing hub 18.

There is a peculiar and special interdependence 25 between the spring-pressed gland and the pressure lubricating devices as they jointly cooperate to permit the gland to be unfailingly urged against the packing by the yielding spring pressure so as to constantly compensate for the wear taking place on the packing, thus effectively preventing 30 the entrance of sand, grit, or water into a shaft bearing. Thus, it is clear that the pressure lubricating devices are effective to constantly extrude a small amount of lubricant outwardly against the water pressure, while at the 35 same time the gland is being pressed inwardly against the packing by the several springs 64 and the water pressure. As fast as the packing wears away, the springs compensate for the wear and make an effective yielding seal counteracting the 40 pressure of the lubricant. Thus, the cooperating instrumentalities are effective to maintain excellent lubrication and to exclude foreign matter from the interior of the bearing.

The bearing 16 is provided with a plurality of 45 grooved portions 96 which permit the lubricant to more readily flow lengthwise of the shaft. For single screw vessels, these grooves extend to the forward end of the bearing to admit the lubricant from the stern tube into which it enters by 50 way of the lubricant duct 56. For multiple screw vessels, the bearing in addition to a plurality of grooves also has a plurality of passages 98 which communicate with an annular chamber 190 opening into passageways 192 formed in the diagonal 55 legs of the strut casting 20. These passageways communicate with the lubricant duct 56 above referred to. There is a gauge 164 which indicates the pressure at which the lubricant is being supplied.

60 Referring further to the pump 40 and the lubricating cylinder 54 and related parts, the pump is adapted to constantly force the lubricant to the bearing as long as the propeller shaft is turning. Thus, the supply of lubricant at a pre-determined rate is automatically maintained. 65 Means are also provided for periodically replenishing the supply of lubricant to the lubricant cylinder 50 after the piston 52 has traveled to the top of the cylinder and exhausted its supply. The refilling of the piston need only be done at 70 long intervals and the necessity for refilling can be determined by suitable markings on the piston rod 52a which moves upwardly with the piston, therefore, it serves as a telltale.

75 With the pump 40 in operation, oil or other

suitable fluid is drawn from the supply tank 42 and forced into the lower chamber 48 of the lubricant cylinder 50, thus moving the piston upward and extruding the grease from the chamber 54 by way of duct 56 and passages 98 and 5 grooves 96 to the interior of the bearing.

The piston 52 acts in a manner somewhat analogous to a hydraulic ram and its rate of upward movement is controlled by a relief valve 106, located in a pipe 108 communicating with 10 the pump outlet pipe 46 and leading to the bottom of the cylinder 50. The relief valve 106 can be set so as to return part of the pumped liquid to the tank 42 by way of the pipe connection 110. There is a normally closed valve 112 also connected between the pipe 108 and the supply tank 42, which valve is merely opened at the time the piston 52 is being reset to its lower position in order to permit the oil from the chamber 48 to be rapidly returned to the supply tank 42. 20

For quickly filling the chamber 54 of the lubricant cylinder, I preferably provide a lubricant reservoir 114 having a plunger 116 therein. This reservoir has an inlet hopper 118 with a gate valve 120 therein. Steam, compressed air or any suitable pressure medium can be supplied by pipe 122 to the space on the opposite sides of the plunger 116 of the reservoir so as to move it up or down. When the plunger moves upwardly, the lubricant therein is discharged by way of 30 pipe 124 to the top of the upper chamber 54 of the lubricant cylinder. After the cylinder is filled, the valve 126 in said pipe 124 should be closed.

To cause the plunger 116 in the reservoir to move upwardly, a valve 128 in the supply pipe 35 is opened while the valve 130 in the branch pipe 132 leading to the space above the plunger is closed. Thus, the pressure will move the plunger upwardly to force the charge of lubricant through the then open valve 126 to the chamber 54 above 40 the piston 50 of the lubricant cylinder. At this time, the valve 112 of the supply tank will be opened and the fluid below the piston 52 will be returned to the supply tank 42.

To replenish the supply of lubricant in the 45 reservoir 114, valve 128 in the supply line is closed and bleeder valve 134 is opened. With the gate valve 120 closed, the valve 130 is opened. This permits admission of pressure medium within the space in the reservoir 114 above the plunger 50 116 and thus forces it downwardly, the pocketed air or other pressure medium being discharged through the bleeder valve 134. With the plunger 116 at the bottom of the reservoir, the bleeder valve is closed and valve 130 is closed. The gate 55 valve 120 is then opened and the lubricant is inserted through the hopper 118. Then upon closing of the gate valve, the reservoir is in condition to intermittently transfer charges of lubricant to the upper chamber 54 of the piston 60 by proper manipulation of the valves in a manner which will be apparent from the above description.

The apparatus described involving the use of 65 the yieldingly pressed, self wear-compensating packing gland will provide sufficient lubricant to the bearing in the stern tube of the vessel and the lubricant will be forced under substantially constant pressure in direct ratio to the speed at which the propeller shaft rotates. The arrangement is such that the lubricating pressure can be very closely regulated and maintained at a point slightly greater than the water pressure outside and thus in a practical sense there will 70 75

be substantially no opportunity for sand, or grit to find its way into the interior of the bearing.

- Once the apparatus is adjusted, no further attention is required other than filling the system at occasional intervals dependent upon the holding capacity of the lubricant cylinder. This filling operation can be rapidly accomplished by means of the reservoir and plunger mechanism described so as not to interfere with the constant lubrication. Only such an amount of lubricant as is necessary to replace a small amount forced past the packing gland is required to maintain the constant pressure in the stern tube. The operation is such that it is entirely automatic and when the pressure in the stern tube bearing reaches a predetermined point, striking a balance with the outside water pressure and the yielding pressure exerted against the gland by the springs, an immaterial quantity of lubricant is expended. Should the lubricant pressure momentarily drop as the result of leakage past the spring-pressed packing gland, additional lubricant will be immediately and automatically fed to replace the loss and to restore the pressure balance to normal. While I have described with great particularity the specific embodiment of the invention herein illustrated, it is to be understood that various modifications and substitutions of equivalents may be made by those skilled in the art without departure from the invention as defined in the appended claims.

What I claim is:—

1. A seal for a submerged shaft, having a cas-

ing, a bearing sleeve mounted therein, said bearing sleeve having a recessed packing chamber at one end, a packing wholly enclosed in said chamber, a gland having one end slidable in the chamber and engaging said packing, a chambered casing bolted to the bearing sleeve and wholly enclosing the gland and circumferentially spaced springs interposed between one end of said chambered casing and said gland for yieldingly pressing the latter against said packing, said casing carrying longitudinally extending circumferentially spaced guide pins for said springs and having longitudinally extending grooves and said gland having lugs making a sliding fit therewith.

2. A seal for a submerged shaft, having a casing, a bearing sleeve mounted therein, said bearing sleeve having a recessed packing chamber at one end, a packing wholly enclosed in said chamber, a gland having one end slidable in the chamber and engaging said packing, a chambered casing fixedly secured to the bearing sleeve and wholly enclosing the gland, and circumferentially spaced springs interposed between one end wall of said chambered casing and said gland for yieldingly pressing the latter against said packing, said end wall of the casing carrying longitudinally extending circumferentially spaced guide pins for said springs, the chambered casing and the gland having coacting interengaging portions allowing a sliding axial movement of the gland relatively to the chambered casing.

HAROLD A. GUTHANS.
